UNITED STATES PATENT OFFICE

2,582,667

COOLANT DEVICE FOR TOOLS

Edward K. Allen, Jr., Worcester, Mass., assignor
to Leland-Gifford Company, Worcester, Mass.,
a corporation of Massachusetts

Original application May 9, 1947, Serial No.
747,052, now Patent No. 2,491,635, dated De-
cember 20, 1949. Divided and this application
August 4, 1949, Serial No. 108,623

1 Claim. (Cl. 77—62)

1

This invention relates to coolant devices for directing lubricants and coolants to tools and also to the work the tool is operating upon.

The principal object of the invention is to provide a device of the class described comprising a new and improved tool bushing which may be made in standard sizes for replacement and interchangeability, said bushing including means for providing correct placement of the coolant relative to the tool and to the work, and also into the groove, hole, etc., that is being machined, so as to flush out and break chips to prevent interference with the tool, and at the same time eliminating bulky and interfering coolant pipes and also to generally improve lubrication and coolant devices for various types of tools, thus reducing tool wear and increasing cutting efficiency.

Further objects of the invention include the provision of new and improved tool bushings and liners which incorporate therein coolant passages formed in the bushings and liners in such a manner that the bushings can be located in the liners without regard to rotative positioning thereof and to at all times receive the coolant supply uniformly without the necessity of piping to achieve the desired result; and the provision of a novel guide bushing for tools in which bushing there are provided passages for directing coolants and lubricants to the tool in a direction in general the same as the direction of the tool feed, so that the tool is maintained clean and free from chips; and the coolant, at the same time, is directed to the hole which is being machined out by the tool so as to flush the same and clean out and break the chips.

Other objects and advantages of the invention will appear hereinafter.

Reference is to be had to the accompanying drawings, in which:

Fig. 1 is a vertical sectional view through a work clamping device in which the present invention may be used, and illustrating the construction and operation thereof;

Fig. 2 is an enlarged vertical section through a bushing and liner embodying the present invention;

Fig. 3 is a bottom plan view of the bushing and liner shown in Fig. 2; and

Fig. 4 is a view in elevation of the bushing.

In order to efficiently cool and lubricate cutting tools it has been necessary in the prior art to provide cumbersome and bulky pipes to direct the coolant fluids to the places desired and it is often a difficult matter to design such piping so that it will not interfere with the operation of

2

the machine. The present case is directed to a new and improved coolant and lubrication system for cutting tools which obviates the use of pipes and also improves the cooling and lubrication thereof.

As shown in Fig. 1, there is provided a base 10 which may be secured to a machine bed by any convenient means. The base 10 in the present case is provided with a generally vertically-arranged standard 12 having a vertically movable rack 14 therein, said rack being operated by means of a gear 16 oscillated by a handle 18.

The rack 14 is secured at its top to a clamping head or support 20 which moves up and down therewith. Said head or support is provided with a tool guiding bushing 22 which is in turn located in a liner 24 in a hole in the clamping head 20.

The liner and the bushing are of course replaceable and interchangeable for different sizes of tools as for instance the drill bit 26 illustrated herein.

The work-piece is indicated at W and is clamped between base 10 and clamping head 20 by means of an element 28 which may be integral with liner 24. However, this element need not be integral with the liner but may be mounted in any way desired, and in Fig. 2 the liner is shown by itself and without the clamping element 28.

In any case, however, the element 28 is provided with a hole 30 for receiving and directing coolant and lubricating fluids and is also provided with a conical surface 32 to aid in centering the work W, the surface 32 intersecting a side wall or hole 30 so as to allow the work to receive the coolant.

The base 10 is provided with a coolant inlet 34 which leads to a vertical hole 36 aligned with a similar hole 38 in the head 20. A valve 40 is arranged in the two holes, being secured to the head and slidably in the hole 36. The valve is provided with an opening 42 communicating with a passage 44 therein, passage 44 in turn communicating with a passage 46 in head 20 so that when the valve is open, coolant fluids flow from the inlet 34 through the valve 40 into passage 46 and into the liner and bushing to the tool as will be hereinafter more fully described.

It will be understood that as the head 20 is brought down by means of rack 14 under influence of the handle 18, the passage 42 will become aligned with inlet 34 so that the valve is open, but when the clamping head is up, the passage 42 is closed in the hole 36 and the fluid will now flow. Also, when the clamping head comes down, it clamps the work in a well known

manner so that when the work is clamped, the coolant flows, but when the work is unclamped, the coolant is shut off.

When the clamping head is down and the valve is open, passage 42 is aligned with a pair of diverging passages 48 which lead to passage 30 and the work-piece.

The details of the liner and bushing are shown in Figs. 2 to 4 and it will be seen that the liner 24 actually is a simple sleeve or hollow cylinder which has a flange at 50 to position the same in the hole in the clamping head 20, and it is also provided with a through hole or aperture in the side wall as at 52, this hole or aperture aligning with passage 46.

The bushing is provided with a flange 54 to position the same on the liner and it also has an annular groove 56 extending all the way around it in position to be aligned with hole or aperture 52, and therefore passage 46, to receive the coolant fluids.

The annular groove 56 is provided with a conical wall at 58 and a plurality of converging annular passages 60 are formed leading down from said conical surface of the bushing. These passages 60 are at such an angle as to direct coolant to the tool 26 and into the flutes thereof so as to perform the desired function of cooling and lubricating the tool and also cleaning the same of chips.

It will be seen that this invention provides tool liners and bushings which may be made standard, releasable, and interchangeable, as is the practice at the present time, but with the additional advantage of optimum placement of coolant as respects both the tool and the hole being machined in the work, and in the absence of interfering and bulky pipes. The bushings of the present invention can be located in the liners without regard to rotational positioning, and the coolant supply will act as a chip breaker as well

as chip remover during the operation of the tool. Also, this invention provides a uniform supply of coolant so as to reduce tool wear and increase the cutting speed and general efficiency of the machine.

This application is a division of my pending application Serial No. 747,052, filed May 9, 1947, and issued as U. S. Patent Number 2,491,635 December 20, 1949.

Having thus described my invention and the advantages thereof, I do not wish to be limited to the details herein disclosed, otherwise than as set forth in the claim, but what I claim is:

In a machine tool comprising a head having a lubricant carrying passage, a tool guiding and lubricating device on said head comprising a tool guiding bushing and a liner receiving said bushing, said liner having a radial aperture through a wall thereof communicating with said lubricant carrying passage in said head, said bushing having an exterior annular groove aligned with said aperture in the liner and a series of downwardly and inwardly directed passages extending from said annular groove solely to the inner surface of the bushing at points spaced from the lower end of the bushing, whereby the lubricant is ejected directly onto a tool in said bushing and is substantially confined between the bushing and the tool in said bushing.
